1 Claim

ABSTRACT OF THE DISCLOSURE

A fish hook barb and point sharpening hone that provides a body consisting of abrasive material and having two opposing lobes and a rounded bottom and a concave upper surface. The side lobes and rounded bottom supply many sized arcs for sharpening the barb and point of different size fish hooks. The concave upper surface is also useful mainly in sharpening the fish hook point.

My invention is a piece of abrasive material specially shaped to sharpen the point and holding barb of fishhooks.

The main object of this invention is to provide a low cost, efficient, lightweight hone, that will safely sharpen the point and holding barb of many different sizes of fishhooks.

Another object is to provide a hone that can be held in the hand and sharpen a held or stationary hook.

An additional object is to provide a hone that can be held stationary and the hook moved to sharpen the point and holding barb.

More uses and advantages will be apparent from the following specification.

My invention is illustrated in the accompanying drawings, in which like characters denote corresponding parts.

FIG. I shows the hone 1, with a large lobe 2, oblong in cross section, a smaller similar opposing lobe 3, and an upper concave surface 4.

FIG. II is the same, but also shows a fish hook in contact with the larger lobe 2 upper rounded surface; 40 where it can be pushed forward to sharpen the barb and pulled back to sharpen the point.

FIG. III shows the rounded bottom surface being used to sharpen the barb and point on a larger fish hook.

2
FIG. IV shows the hone on the under side where it can be moved forward, backward, or rotated to sharpen the point and barb of a fish hook.

FIG. V shows the hone on the outside where it can be used to sharpen the point by a back, forward, or rotative movement.

This hone can be constructed of ceramic material, such as aluminum oxide. This material will make a low cost, hard material hone, that will last for years.

Fish hooks are blunted in use in many different ways, also a new hook's point and holding barb are not as sharp as many experienced fishermen would like to have them be.

It is understood that various changes in shape, size, arrangement of parts, may be resorted to without departing from the spirit of my invention, or the scope of the subjoined claim.

Having thus described my invention, I claim:

1. A sharpening hone for the barb and point edges of a fishhook comprising in combination:
  - (a) a hone made of abrasive material,
  - (b) said hone having two lobes, oblong in cross section, positioned opposed to each other and longitudinally,
  - (c) said opposing lobes are joined on the bottom by a convex portion of the hone,
  - (d) and the top side of the hone between said opposing lobes forms a concave surface.
